WORKMAN'S TIME RECORDER

Edward G. Watkins and James A. Dell, Gardner, Mass., assignors to Simplex Time Recorder Company, Gardner, Mass., a corporation of Massachusetts

Application September 24, 1935, Serial No. 41,924

9 Claims. (Cl. 234—43)

This invention relates to recorders for making a printed time record on workmen's individual time cards.

More specifically, the invention relates to a time recorder in which the card guide or chute is shifted laterally at predetermined intervals which are commonly determined by the particular working hours in force where the recorder is in use.

One important object of our invention relates to the provision of improved means for shifting the card chute periodically by actuating devices which are indirectly driven from the time mechanism, so that the intermittent chute-shifting load does not react directly on the time mechanism.

More specifically, we provide means for storing power during one time period such as twenty-four hours, which power is thereafter transferred and made available for shifting the card chute at successive intervals during the next time period.

We also provide improved means for preventing a registration unless the card chute is in some one of its predetermined positions.

Our invention further relates to arrangements and combinations of parts which will be herein-after described and more particularly pointed out in the appended claims.

A preferred form of the invention is shown in the drawings, in which

Fig. 1 is a plan view of the card chute and associated parts;

Fig. 2 is a plan view of a portion of the time recorder casing;

Fig. 3 is a front elevation of the parts shown in Fig. 1;

Fig. 4 is a left-hand side elevation, looking in the direction of the arrow 4 in Fig. 1;

Fig. 5 is a detail sectional view, taken along the line 5—5 in Fig. 3;

Fig. 6 is a sectional plan view, taken along the line 6—6 in Fig. 4;

Fig. 7 is a side elevation of the control disc;

Fig. 8 is a detail sectional view, taken along the line 8—8 in Fig. 7;

Fig. 9 is a detail sectional plan view, taken along the line 9—9 in Fig. 4;

Fig. 10 is a detail front elevation, looking in the direction of the arrow 10 in Fig. 4;

Fig. 11 is a detail sectional front elevation, taken along the line 11—11 in Fig. 4;

Fig. 12 is a side elevation of the circuit-closing devices, taken substantially along the line 12—12 in Fig. 2, and

Figs. 13 and 14 are side elevations of certain parts appearing in Fig. 4 but shown in different positions.

Referring to the drawings, we have shown a card chute 20 (Fig. 3) mounted to slide trans-

versely on fixed horizontal guide rods, one of which is shown at 21. The chute 20 is provided with a card rest 22 (Fig. 3) slidable in grooves in the vertical side members 23 of the card chute and shifted intermittently vertically at the end of each day by time controlled actuating mechanism, not shown, and forming no part of our present invention.

Guide plates 24 and 25 (Fig. 3) are secured to the front of the card chute and are spaced substantially forwardly therefrom. The card chute 20 is relatively slidable transversely along a rack bar 26 mounted in openings in the guide plates 24 and 25, and a stop pin 27 on the rack bar engages the left-hand side of the guide plate 25 and limits movement of the card chute to the left relative to the rack bar.

An elongated coil spring 28 is connected at one end to a stud 29 on the rack bar and at the other end to a stud 30 on the guide plate 25. The card chute may thus be moved yieldingly to the right relative to the rack bar 26, from the position shown in Fig. 3, but is held by the stop 27 from relative movement to the left.

The teeth of the rack bar are engaged by a pinion 32 (Fig. 3), loosely mounted on a cross shaft 33 and yieldingly moved clockwise by a coil spring 34 having its lower end fixed to the recorder frame and having its upper end connected to a flexible metal band 35 wound around the hub 36 of the pinion 32 and secured thereto by a screw 37.

A collar 40 (Figs. 1 and 6) is secured to the outer end of the cross shaft 33 and has an axially projecting lug 41 engaged by a radially disposed pin 42 on the hub 36. The lug 41 and pin 42 thus constitute a lost motion connection between the shaft 33 and the pinion 32.

With this construction, the transverse position of the rack bar 26 and card chute 20 is normally controlled by the shaft 33 but the card chute and rack bar may be temporarily shifted manually to the left for irregular registration, in which end the pinion 32 rotates freely relative to the shaft 33 and temporarily elongates the spring 34.

If on the other hand it is desired to shift the card chute to the right manually for an irregular registration, the guide plates will slide freely along the rack bar 26, at the same time tensioning the spring 28. As soon as the card chute is released from displacement in either direction, it will return immediately to its predetermined setting.

The mechanism for making the impression forms no part of our present invention and is substantially similar to that shown in the prior application of Edward G. Watkins, Serial No. 20,140, filed May 7, 1935.

This impression making mechanism is shown,

however, on Figs. 3, 4 and 12 and briefly comprises a lever 44 (Fig. 12) pivoted at spaced points 45 (Fig. 2) to the recorder casing C and having a finger plate 46 extending across the front of the recorder above and just to the rear of the card chute.

A spring 47 (Fig. 12) normally holds a stop pin 48 against an upright bar 49. The lower end of the lever 44 engages a member 50 (Figs. 1 10 and 12), one end of which is secured to a plunger 51 slidable in fixed bearings 52. An intermediate portion of the member 50 is slidable in a fixed slotted guide plate 53, and the forwardly offset outer end of the member 50 is threaded to receive a screw 54 forming an adjustable abutment adapted to be positioned in a recess 55 (Fig. 4) formed in the upper end of a lever 56 mounted on a fixed pivot 57.

The coil spring 58 (Fig. 1) engages a washer 20 59 on the plunger 51 and forces the washer rearward against a cross-pin 60, which in turn engages the front side of the rear bearing 52. The front end of the plunger 51 is adapted to enter some one of a series of openings 62 (Fig. 5) in 25 a bar 63 fixed to and movable transversely with the card chute 20 when the card chute is in any one of its predetermined lateral positions. When thus aligned, the finger plate 46 may be operated to move the plunger 51 forward. If the card chute 30 is not in any one of its regular positions, the plunger will engage the rack bar 63 between the holes 62 and movement of the finger plate will be prevented.

The lever 56 (Fig. 4) is provided with a latch 35 65 adapted to engage a plate 66 on the upper end of a yielding member 67 which supports a contact stud 68. When the lever is moved forward by pressure on the finger plate, the circuit is closed and a solenoid coil 69 operates a plunger 70 to turn 40 the hammer shaft 71 and cause a hammer 72 (Fig. 3) to force the card against the type wheels to make an impression.

As the plunger 70 rises, a plate 74 (Fig. 4) movable therewith engages the outer end of the 45 latch 65, lifting it away from the plate 66 so that the contacts yieldingly separate and the hammer circuit is broken. A light coil spring 75 maintains the lever 56 yieldingly in rearward position, and a stop 76 limits forward movement thereof.

50 For the purpose of moving the card chute manually laterally for irregular registrations, we provide a plate 80 (Fig. 2) mounted to slide transversely in the casing C and having a forwardly projecting thumb piece 81 with an opening 82 55 through which insignia on the casing may be observed. Studs 83 extend downward from the slide plate 80 and engage the side edges 84 (Fig. 5) of the card chute 20.

The operator by grasping the thumb-piece 81 60 is thus able to move the card chute from its regular position in either direction, such movement being permitted by the yielding connections previously described.

The pinion cross shaft 33 (Fig. 6) is provided 65 at its rear end with a bevel pinion 85 engaging a bevel pinion 86 on a short shaft 87 pivoted in fixed bearings and provided with a pinion 88 engaged by the teeth of a segment gear lever 90 (Fig. 4). The lever 90 is mounted on a fixed 70 pivot 91 and is drawn yieldingly upward by a spring 92 connected between a fixed stud 93 and a stud 94 on the lever 90.

A spring plate 95 (Figs. 4 and 9) is secured to 75 the lever 90 by a screw 96 and has a yoke con-

nection to the slotted outer end of a stud 97 mounted to slide in a bearing 98 on the lever 90.

The inner end of the stud 97 successively engages different flange plates 100 (Figs. 7 and 8) secured to the outer face of a disc 101 mounted 5 on a shaft 102^a (Fig. 6) which makes one revolution in twenty-four hours and which is continuously rotated by the type wheel driving mechanism.

The flange plates 100 are of substantially triangular cross section as shown in Fig. 8, with the thicker edge portion at the outside. The disc 101 rotates in an anticlockwise direction and the leading end of each flange plate is beveled circumferentially as indicated at 102, while the following 15 end of each plate is sharply undercut as indicated at 103.

The different flange plates are provided with segmental ribs 104 (Fig. 8) fitting corresponding concentric grooves 105 in the face of the disc 101. 20 The disc is provided with concentric series of tapped holes 106 (Fig. 7) to receive screws 107 extending through slots 108 in the flange plates 100.

By placing the screws in selected holes and 25 adjusting the plates angularly with respect to the screws and disc, the flange plates may be secured in any desired angular relation on the face of the disc 101, and each flange plate may be of such segmental length as is found desirable. 30

Assuming that the parts are in the position shown in Fig. 13, the spring 92 acts to pull the stud 97 upward against one of the flange plates 100 and this action is supplemented by the spring 34 (Fig. 3) acting through the cross shaft 33 and 35 gear connections which also tend to swing the segmental gear 99 and stud 97 upward.

No upward movement can take place, however, until the disc 101 has rotated sufficiently so that the stud 97 can snap off of the rear or undercut 40 end of the flange plate 100 with which it is engaged, whereupon the segment gear will move upward and the card chute will move to the right in Fig. 3 until the stud 97 engages the next inner flange plate 100. This successive holding and release action will continue until the stud 97 engages the hub 110 of the disc 101, in which position the card chute occupies its extreme right-hand position.

It will thus be seen that the disc 101 and plates 50 100 merely act to alternately hold and release the segment gear 99 for movement under the influence of the springs 92 and 34 but that the disc 101 furnishes no power for movement of the card chute or its associated parts. 55

When the stud 97 is moved inward and engages the hub 110 and the card chute 20 is in its extreme right-hand position, some provision is necessary for resetting the apparatus and for returning the card chute to the left, an action ordinarily taking place at midnight.

We will now describe the mechanism by which this resetting is accomplished.

We provide a cam 112 (Fig. 13) mounted on a cam shaft 113 and connected by gears 114 and 115 65 (Figs. 4 and 10) to the driving shaft 102^a (Fig. 6) by which the disc 101 is rotated. The gears 114 and 115 are of equal size so that the cam 112 rotates once in twenty-four hours in a clockwise direction.

The cam 112 is provided with a pivoted loose tip 117 (Fig. 13) for purposes of quick release of the cam roll 118 which is mounted on an arm 119 swinging about a fixed pivot 120. A heavy coil spring 121 is connected between a stud 122 on the 70 75

arm 119 and another stud fixed to the recorder frame but not shown. As the cam 112 rotates, the roll 118 and arm 119 are raised and the heavy spring 121 is tensioned.

5 A hook 130 (Fig. 13) is pivoted at 131 on the arm 119 and a spring 132 normally holds the hook 130 against a stop pin 133 in the segment gear 90. As the arm 119 is moved upward, however, by the cam 112, a lug 134 on the hook 130 is 10 engaged by an arm 140 mounted on a fixed pivot 141 and yieldingly held downward against a stop pin 142 by a spring 143.

The spring 143 is strong enough to overcome the spring 132 and to swing the upper end of the pivot 120 rearward to the position shown in Fig. 14 as the arm 119 approaches its upper limit of movement. In such rearward position the hook 130 overlies a stud 145 (Fig. 14) in the segment gear 90.

20 When the cam roll 118 thereafter drops off of the cam 112, the hook 130 pulls the segment gear 90 down until the lower surface 146 (Fig. 4) thereof engages a fixed stop plate 147. By such movement of the segment gear, the card chute is returned to extreme left-hand position by the power stored in the heavy spring 121 and without direct dependence on the driving power of the time mechanism.

During this downward movement of the segment gear 90, the stud 97 ratchets outward over the outwardly tapered flange plates 100 and snaps again into operative position outside of the outermost flange plate, as shown in Fig. 4.

As soon as the cam 112 begins to lift the arm 35 119, the stud 97 will engage the outermost flange plate 101, and still further upward movement of the arm 119 will cause the hook 130 to clear the stud 145, thereupon it will be swung to the position indicated in Fig. 13 by the spring 132 and will 40 not thereafter interfere with the intermittent upward movement of the segment gear.

By this improved driving mechanism, we thus utilize the slow continuous rotation of the cam 112 to store up energy in the spring 121 during 45 an entire twenty-four hour period, which energy is released when the roll 118 drops off the cam point 117 and is then applied to return the card chute to the left and to tension the springs 34 and 92. The entire action is automatic and the slow 50 continuous and uniformly resisted movement of the cam 112 does not place an undue load on the time mechanism.

Having thus described our invention and the advantages thereof, we do not wish to be limited to 55 the details herein disclosed, otherwise than as set forth in the claims, but what we claim is:

1. In a time recorder, a card chute, a hammer device, actuating mechanism therefor including an electric circuit and a circuit-closing switch, 60 a bar mounted on said chute and having spaced holes therein, and a plunger slidable through any one of said holes when said hole is in a predetermined position, said plunger and bar cooperating to prevent closing of said switch when said plunger 65 is out of alignment with one of said holes.

2. In a time recorder, a card chute, a hammer device, actuating mechanism therefor including an electric circuit and a circuit-closing switch, a bar mounted on said chute and having spaced 70 holes therein, and a plunger slidable through any one of said holes when said hole is in a predetermined position, and said plunger and bar cooperating to prevent closing of said switch when said card chute is not in some one of its normal 75 operating positions.

3. In a time recorder, a card chute, a spring actuated cross shaft, a pinion mounted on said shaft and having a driving connection thereto which permits limited lost motion between said pinion and shaft, and a rack bar slidably and yieldingly mounted on said card chute and engaged by said pinion. 5

4. In a time recorder, a card chute, a spring actuated cross shaft, a pinion mounted on said shaft and having a lost motion driving connection thereto, a rack bar engaging said pinion and slidably mounted on said card chute, a spring acting to slide said card chute in one direction relative to said bar and a stop on said bar effective to limit such sliding movement. 10

5. In a time recorder, a card chute, a rack bar slidably mounted thereon, a spring to move said chute longitudinally in one direction relative to said bar, a stop on said bar to limit such movement, time-controlled means to move said bar and chute periodically and automatically as a unit in said direction, and a yieldable connection between said time-controlled means and said bar, which connection yields to permit said bar and chute to be moved manually in the opposite direction and which restores the normal operation of said time-controlled means when said bar and chute are released from manual control. 15

6. In a time recorder, a card chute, time-controlled means including a segment gear to shift said card chute, a timing disc having a series of concentric segmental flange plates, a stud on said segmental gear engaging said flange plates successively as said disc is rotated and a spring for said stud, said flange plates having outwardly inclined inner faces and said stud being yieldingly and axially movable in said segmental gear and being thereby yieldingly movable past said flange plates when said gear and stud are swung outward away from the axis of said disc, and means 30 to move said gear and stud outward at predetermined time intervals. 35

7. In a time recorder, a card chute, spring means to move said card chute at intervals in one direction, a pinion connected to shift said card chute in the opposite direction, a segmental gear having a stud, a pivoted arm, a hook on said arm, a spring to hold said hook normally clear of said stud, means to swing said hook over said stud as said arm and hook are raised, a continuously rotated cam effective to raise said arm and hook and to thereafter release said arm and hook, and a heavy spring connected to said arm and effective to depress said segmental gear and thereby rotate said pinion to restore said card 50 chute to initial position when said arm is released by said cam. 55

8. In a time recorder, a card chute, a rack bar slidably mounted thereon, a stop on said bar, a spring to hold said chute yieldingly against said stop, and manual means to move said card chute relative to said bar away from said stop and against the action of said spring. 60

9. In a time recorder, a card chute, a hammer device, electro-magnetic actuating means therefor, an electric circuit for said means including a circuit-closing switch, means to move said card chute to a plurality of different lateral operating positions, and means to block said switch from 70 closing movement when said chute is out of alignment with some one operative position. 65
